FIG. 1

FIG. 2

FIG. 3

FIG. 4

FIG. 1 is a perspective view of a pair of spectacles showing my new design;

FIG. 2 is a front elevational view thereof;

FIG. 3 is a front elevational view of another embodiment of my new design;

FIG. 4 is a front elevational view of still another embodiment of my new design.

The characteristic features of my design reside in the specific configuration of the bridge as best seen in FIGS. 2, 3 and 4.

The side not shown has substantially the same appearance as the side shown.

I claim:

The ornamental design for a pair of spectacles, substantially as shown and described.
